ANTIRACING CONTROL-EQUIPMENT

Lloyd J. Hibbard, Pittsburgh, Pa., assignor to
Westinghouse Electric Corporation, East Pitts-
burgh, Pa., a corporation of Pennsylvania

Application June 21, 1951, Serial No. 232,811

8 Claims. (Cl. 317—139)

1

My invention relates to anti-racing interlocking-means for a control-equipment consisting of a plurality of contactors, which are controlled by a plurality of relays, which are in turn controlled from one or more master controllers. In its broadest aspects, my invention is applicable to any control-equipment using relatively small, fast, light-duty relays, for controlling a plurality of heavy, relatively slow contactors, which have main-circuit contacts which have to be operated in a predetermined order or sequence. My invention has more particular relation to a multiple-unit or multiple-truck train-control for electrically propelled vehicles, in which a bundle or cable of a plurality of control-wires are used, in what is known as a train-line, for carrying the controlling-currents from one cab or car to another, or even from one motor-driven truck to another.

The relays which energize the contactor-controlling coils are known to be subject to occasional troubles or faulty operations, due to jammed contacts or welded contacts, which prevent a relay from opening when it should, or dirty or gritty contacts, which may prevent a relay-contact from closing when it should. This is true, even if the controller and the controlling-circuits for the relays are in perfect operating-order. For these reasons, it has been the practice, for several decades, to put interlocks on the contactors, which carry the all-important main-circuit contacts. These contactor-interlocks have, under normal circumstances, successfully and adequately controlled the sequence of contactor-operations, in accordance with whatever contact-sequence has been required, in any given case; but this successful operation has not been maintained when there has been contactor-racing, that is, when abnormal conditions have arisen, in which there has been a simultaneous energization of the operating-coils of two or more contactors which ought not be closed at the same time.

Under such switch-racing circumstances, all of the simultaneously energized contactors would start to close at once, and it would be a race to determine which contactor closed first. Usually, all of the energized contactors would become simultaneously closed or energized, at least for a brief moment, before the proper interlocking functions could come into play and force the reopening of the contactors which should not have been closed. Meanwhile, however, the faultily closed contactor-contacts may have done great damage to the main power-circuits

5 or apparatus controlled by said contactors, occasionally resulting in the burning out of apparatus or the starting of serious fires, and always resulting in serious burning of the contactor-contacts. This has constituted a serious problem, which has been recognized in the industry, at least since 1936. Prior to my present invention, no practical corrective-means have been conceived, having the necessary simplicity to make them commercially acceptable on the equipments in question.

10 So far as my broadly conceived invention is concerned, it is immaterial why or how a plurality of contactors, which should have been operated sequentially, were occasionally operated simultaneously. As a matter of interest, however, and for the better understanding of the circumstances with which my invention is associated, it may be mentioned that such faulty simultaneous energizations might result from overlapping master-controller fingers or contacts, due, for example, to stopping the master-controller between notches, or from short-circuits or grounds on the train-lines or other control-wires, due to moisture from escaping steam from nearby steam-lines, or the falling of control-covers against terminals, or from improper connections during extensive overhauls when the flag-markings on the wire-terminals have become obliterated.

15 It is a difficult problem to provide a simple means for causing a large group of electrically controlled main-circuit contact-making devices to operate sequentially, according to a predetermined sequence, when their control-coils are 20 simultaneously energized. As a rule, out-interlocks will have to be provided, in any case, on these main-circuit contact-making devices, for serial inclusion in either the positive or negative supply-lead which supplies electrical 25 controlling-energy for these main-circuit contact-making devices; and sometimes, when it is necessary to control the retrogression-sequence as well as the progression-sequence, it is necessary to provide a series of out-interlocks in both the negative and the positive supply-leads. 30 There are certain requirements governing the successful operation of these out-interlocks, while at the same time obtaining the necessary operating-characteristics of the electrically controlled main-circuit contact-making devices, so that it is not feasible, in the installations with 35 which my present invention is concerned, to make the necessary out-interlocks open so early, 40 during the closing-movement of the contact-

making device on which it is located, that it will deenergize the next contact-making device of the sequence quick enough, in the event that both contact-making devices are simultaneously energized, to prevent said next contact-making device from continuing to close, by its own inertia, on the electrical closing-impulse which was given to it prior to the opening of the out-interlock of the preceding contact-making device of the series. This is called switch-racing.

Of course, if there is enough space available, on which to put all the necessary interlocks or auxiliary switch-contacts which could be desired, it would be possible to prevent this switch-racing by using a large number of in-interlocks on the main-circuit contact-making devices, but these in-interlocks could not be serially included in either the positive or negative supply-lead, which supplies electrical controlling-energy for a series of main-circuit contact-making devices, but these in-interlocks would have to be duplicated in the individual circuits of each one of the control-coils for the contact-making devices which are to be affected. In small operations, where there are only three or four steps in the sequence, it might be possible, in some cases, to use this sort of in-interlock sequential control, but even in such small operations, the required number of interlocks and the complexity of the circuit-connections would be quite serious.

In large modern railway-control operations, where there are ten, twenty, or even thirty steps in the required sequential control, there simply is not room to provide the large number of electrical interlocks which would be needed to prevent the possibility of switch-racing, in the event of the simultaneous energization of the control-coils of a plurality of switches or contact-making devices, even though the user of the apparatus could tolerate the maintenance-burden of supervising the large number of interlocks and the complicated wiring-circuits which would ensue.

My present invention is related to a control-equipment in which it is necessary, for reasons other than switch-racing, to provide sequence-relays, or small fast-operating auxiliary relays, for closing the individual control-coil circuits of the several main-circuit contact-making devices. These auxiliary relays are necessary, for example, whenever the electrical energy which is required by the control-coils of the main-circuit switches is larger than can be successfully handled directly by the master-controller, or whenever a reasonably limited (large) number of train-wires have to be used, in multiple-unit control-systems involving two or more master-controllers, only one of which will be in use at any given time. However, these auxiliary relays, by reason of their very lightness and small-energy requirements, are subject to occasional malfunctions, resulting in failure to either open or close their contacts when they should, so that the interlocks still have to be used on the main-circuit switches or contact-making devices, regardless of the use of auxiliary relays or their control.

My invention solves all of the foregoing difficulties in a most simple and direct manner. It duplicates, in the relay-circuit control, the out-interlock controls which are used on the main-circuit contactors, or at least the progression-sequence interlocks of said main-switch control. In this way, the relays will race, if they should be simultaneously energized, but even though the relays do race, the improperly closed relays will immediately drop out again, under the control of

their out-interlocks, and these relays are so fast in their operations, that the heavy, sluggishly-operating main switches will not begin to move, or will not make any substantial movement, before the relays have finished their racing, and have finished sorting themselves out, and have settled down, with only the relays closed, which need to be closed, to constitute the first relays of the desired sequence. In this way, the switch-racing has been transferred from the main switches, where great harm will be done by the racing, to the auxiliary relays, where no harm is done by the racing, and racing is prevented in the main-switch assembly.

With the foregoing and other objects in view, my invention consists in the circuits, apparatus, combinations, parts, and methods of design and control, as hereinafter described and claimed, and illustrated in the accompanying drawing, in which the single figure is a diagrammatic view of circuits and apparatus of a very much simplified, and somewhat idealized, control-equipment which involves my invention in an illustrative application or form of embodiment of the invention, showing only the smallest number of parts which are necessary to fully illustrate the invention, and omitting the numerous other safeguards and refinements which make up a modern railway-control installation.

The control-equipment which I have illustrated in the drawing is shown applied to a locomotive or other railway-vehicle, which is represented as comprising a pantograph 13 which receives power by making a sliding contact with a single-phase trolley-wire 14. The pantograph 13 energizes a step-down transformer 15 on the locomotive, and this transformer is provided with a multi-tapped secondary-winding 16. In the particular locomotive which is illustrated, my improved control-equipment involves a group of electrically controlled main-circuit contact-making devices which are actually tap-switches or contactors which are numbered from C₁ to C₁₂, for selecting and controlling the secondary taps of the transformer.

In the particular locomotive-installation which is illustrated, the traction-motors are direct-current motors, only one of which is illustrated, having an armature A. This motor is energized from the selected taps of the transformer-secondary 16, through rectifiers 17 and 18, the return-circuit for the motor being completed through a ripple-reducing choke-coil 19, and the midpoint tap-connection X of the transformer-secondary 16. The anode-leads 21 of the rectifiers 17 and 18 are shunted by an alternating-current filter 22, as described and claimed in my application Serial No. 120,331, filed October 8, 1949, now Patent No. 2,636,995, April 28, 1953. In series-circuit relation to the anode-leads is a pair of mutually coupled anode-lead reactors 23, as described and claimed in my copending application Serial No. 210,390, filed February 10, 1951, now Patent No. 2,636,997, April 28, 1953. The motor is shown as comprising, in addition to the armature A, a serially connected interpole-winding 24 and a series main-field winding 25, which is connected through a reverser 26.

This particular type of rectifier-powered locomotive is shown merely as an example of one application of my invention, which is applicable also to other tap-changing controls, and also to main-circuit switches or contactors which are used to control circuits other than transformer-taps.

The tap-switches or contactors C_1 to C_{12} are provided with contactor-controlling coils 31 , which may be either solenoids for magnetically operating the contactors, or, more usually, valve-magnet coils for controlling air-engines (not shown), which constitute the actual motivating-means for operating the switches or contactors, as is well known in the art. In any event, these main-switches or contactors C_1 to C_{12} are large heavy-duty devices, which are relatively sluggishly moved. In the drawing, the sluggish response, or delayed action, of the main contactors C_1 to C_{12} is diagrammatically indicated by means of a short-circuited coil or slug 32 , which is diagrammatically shown as a second circle surrounding the circle which represents the controlling-coil 31 , and which is intended to represent any kind of means for producing a relatively slow action, either by reason of the large inertia of heavy parts, or by way of opening a magnet-valve (not shown), for initiating the operation of an air-engine (not shown), all of which takes a certain amount of time. So far as my present invention is concerned, the essential feature is that there should be a relatively sluggish or delayed response of the main contactors C_1 to C_{12} , when their respective operating-coils 31 are electrically energized.

Each of these main-circuit contactors C_1 to C_{12} has a main-circuit make-contact (or contacts) 33 which is closed by the response of that contactor. At least some of these main contactors, for example, the contactors C_1 to C_8 in the simplified equipment which is illustrated, are provided with positive-circuit out-interlocks 34 , which are auxiliary control-circuit back-contacts which are opened by a response of the contactor in question. In the illustrated form of embodiment of my invention, another sub-group of these contactors, for example the contactors C_9 to C_{12} , are provided with negative-circuit out-interlocks 35 which are similar, in construction, to the out-interlocks 34 . The circuits for these contactor-interlocks 34 and 35 will be described later on.

In a rectifier-powered locomotive, such as that which is illustrated, the secondary taps are divided into two different groups on opposite sides of the midtap X . Thus, on one side of the midtap, are the taps T_1 , T_2 and T_3 , only three taps being shown, for simplicity of illustration, although it will be understood that ordinarily many more taps would be used, on each side of the midpoint X of the transformer-secondary 16 . On the other side of the midpoint X are corresponding taps, which are designated T_1' , T_2' and T_3' . Two preventive-coils are used, designated 36 and $36'$, respectively, one for each side of the midtap X . The midtaps of the preventive-coils 36 and $36'$ are used, as shown at 37 and $37'$, to energize the rectifiers 17 and 18 .

The terminals 38 and 39 of one preventive-coil, 36 , are connected to the first tap T_1 through the main-circuit contacts 33 of the contactors C_1 and C_3 . These same preventive-coil terminals 38 and 39 are connected to the second tap T_2 , on the same side of the transformer-midtap X , through the main-circuit contacts 33 of the contactors C_5 and C_7 . In like manner, the same preventive-coil terminals 38 and 39 are connected to the tap T_3 through the main-circuit contacts 33 of the contactors C_9 and C_{11} . The other preventive-coil $36'$ has its terminals $38'$ and $39'$ connected, in a similar manner, to the taps T_1' , T_2' and T_3' , on the other side of the midtap X , through the

main-circuit contacts 33 of different pairs of the even-numbered contactors C_2 to C_{12} .

Each of the contactor-controlling coils 31 , of the several contactors C_1 to C_{12} is under the control of a corresponding relatively fast, light-duty, auxiliary sequence-relay X_1 to X_{12} , as the case may be. These relays X_1 to X_{12} are shown as each having a contactor-controlling make-contact (or contacts) 43 , which is connected in series with the contactor-coil 31 of the correspondingly numbered contactor C_1 to C_{12} , as the case may be. These contactor-controlling relay-contacts 43 are closed by a response of the relay which carries the contact. Each of the relays X_1 to X_{12} is provided with a suitable operating-means which includes a relay-controlling coil 44 . This relay-controlling coil 44 may bring about the operation or the response of the relay either directly or indirectly: usually it will be a direct-acting operating-coil or solenoid which magnetically actuates the relay. Each of the relay-controlling coils 44 , of the several relays X_1 to X_{12} , has a correspondingly numbered energizing-circuit lead, numbered 1 to 12 , respectively.

Each of these relays X_1 to X_{12} is also provided with an out-interlock 45 , which is a control-circuit back-contact which is opened by a response of that relay.

The control-equipment includes one or more master-controllers MC , or other controlling-means which is under the control of the engineer or other attendant in charge of the control-equipment. In order to prevent "backstair" circuits, the relay-controlling conductors 1 to 12 are serially connected to unidirectionally conducting rectifiers 47 , one rectifier for each circuit, these several rectifiers being connected between the relay-energizing circuits 1 to 12 , on the one hand, and the controller-energized circuits $1'$ to $12'$, on the other hand. The controller MC is illustrated as a simple drum-controller, having an off-position, and nine running-positions, numbered 1 to 9 , for connecting the desired relay-controlling wires 1 to 12 to the positive bus $(+)$ in the desired sequential order.

It is to be understood, of course, that the illustrated master-controller MC may be any kind or type of controller-means which is capable of performing the sequential relay-controlling functions which have just been mentioned, in whatever order or sequential law may be desired, in any particular case.

I wish it to be also understood that the terms "contactors" and "relays," as used herein, are intended to include any contact-making devices of the broad descriptions which have been given, regardless of any special restricted uses of these terms which may sometimes be adopted in the art.

While my invention is not limited to any one particular application or situation, it was especially designed for, and has been illustrated in connection with, a multiple-unit train-installation, in which the control-energizing conductors 1 to 12 are connected to correspondingly numbered conductors in a train-line 49 , which may be a line running to other cars or locomotive-cabs in the train, or to other motor-operated trucks of a single electrically powered vehicle. As previously explained, such train-lines are subject to short-circuits and grounds, whereby the different line-conductors 1 to 12 may become simultaneously energized: also the controller or controllers MC are subject to faulty contact-operations, the terminals of the con-

ductors 1' to 12' may sometimes be erroneously connected, and one of the relays X₁ to X₁₂ may sometimes fail to open or close one or more of its contacts when the relay should operate. It is under such circumstances that my invention finds perhaps its most important application. It is possible, however, for my invention, or some features of it, to be used in a situation in which the relay-energizing conductors 1 to 12 are always deliberately energized together, leaving the relays to sort out the desired sequential operation, or order of operation, in a manner which will now be described.

In operation, the controller MC is arranged to provide for the orderly closure of the relays X₁ to X₁₂, and hence the main-circuit contactors or switches C₁ to C₁₂, in whatever sequential order may be required of any particular control-equipment. The same holds true for the various interlocks 34, 35 and 45.

In the particular control-equipment which is illustrated, it is desirable that four consecutively numbered contactors, of the main contactors C₁ to C₁₂, shall always be closed at once, in any running-position of the apparatus, and never more than four at once; although, in the transition-periods, when the contactors are dropped out, one at a time, and another contactor is pulled in, so as still to leave four contactors energized, there is an instantaneous transition-period in which the dropping out of the dropped-out contactor pulls in or energizes the contactor which is to be newly actuated in that step of the sequential operation.

Thus, in the illustrated apparatus, it is quite essential that no two of the contactor-switches C₁ to C₁₂ shall ever be simultaneously closed on the same preventive-coil terminal 38, 39, 38' or 39'; it is essential that neither one of the preventive coils 36 or 36' shall ever be impressed with a greater voltage than the voltage between two adjacent taps, such as the taps T₁ and T₂, the taps T₂ and T₃, the taps T_{1'} and T_{2'}, and the taps T_{2'} and T_{3'}; and it is usually quite desirable that the taps T₁, T₂ and T₃ on one side of the midpoint X shall never get further than one voltage-step away from the corresponding taps T_{1'}, T_{2'} and T_{3'} on the other side of the midpoint X. In this way, the equipment prevents the direct short-circuiting of any portion of the transformer-secondary 16, or the application of excessively high voltages across the preventive-coils 36 and 37, which would result in burnouts of these coils, or the production of excessive even harmonics in the alternating-current trolley-wire 14, as a result of excessively unbalanced voltages in the two alternate half-cycles of the rectifier-operation.

I will first describe the control-circuits for the operating-coils 31 of the main-circuit contactors C₁ to C₁₂, because these circuits are old, and have been in use for some time prior to my present invention. The positive relay-supply terminal (+) is connected to a positive relay-circuit terminal 50, which is extended through the serially connected out-interlocks 34 of the contactors C₁ to C₈, respectively, to successively energize the conductors 51 to 58. The negative relay-supply terminal (-) is connected to a negative relay-circuit terminal 60, which is extended, through the serially connected out-interlocks 35 of the contactors C₁₂ to C₅, respectively, to energize the respective circuit-conductors 72 to 65, respectively.

The C₁ contactor-coil 31 is connected between

the circuits 50 and 65, with the X₁ relay-contact 43 in series therewith; the C₂ coil is connected between the circuits 50 and 66 with the X₂ relay-contact 43 in series therewith; and the C₃ and C₄ coils are similarly connected between the circuit 50 and the circuits 67 and 68, respectively, each in series with the make-contact 43 of its associated auxiliary relay X₃ and X₄, respectively.

The contactor-controlling coils of the next four contactors, C₅ to C₈, are connected respectively between the successive positive circuits 51 to 54, and the successive negative circuits 69 to 72, each in series with the make-contact 43 of its own corresponding auxiliary relay X₅ to X₈. Ordinarily, there would be a number of groups of four contactors like the contactors C₅ to C₈, but my drawing has been simplified to show only one.

The contactor-controlling coils of the last four contactors C₉ to C₁₂ are connected, on one side, to the last four positive conductors 55 to 58, respectively, and on the other side they are all connected to the negative conductor 60, each contactor-coil being in series with the make-contact 43 of its correspondingly numbered auxiliary relay X₉ to X₁₂.

The proper operational sequence, in the progressive order of acceleration-control, is maintained by keeping four contactors, and only four contactors, energized at the same time, as called for by the master-controller MC. Thus, the first four contactors, C₁ to C₄, will close first, on the first notch of the controller MC. Then the first contactor C₁ will be deenergized and the fifth contactor C₅ will be energized, but before the C₅ coil can receive current, the C₁ off-interlock 34 must be closed; that is, the first contactor C₁ must open. The sequence of operations thereafter continues, each change consisting in dropping out the lowest numbered of the contactors, and bringing in the next-numbered contactor, until finally the last four contactors C₉ to C₁₂ are energized, corresponding to the highest-voltage secondary-tap connection, and the highest voltage which is applied to the traction-motor A. These are the interlocking contact-controls which control the progressive sequence, and they are accomplished through the action of the positive-circuit off-interlocks 34 of the first eight contactors C₁ to C₈, while the voltage is being progressively increased, in eight successive steps, from its lowest voltage to its highest voltage.

The retrogressive sequence, which is under the control of the negative-circuit off-interlocks 35 of the contactors C₁₂ to C₅, operates as follows. Assume, for example, that the four highest-numbered contactors C₉ to C₁₂ are closed, on controller-position number 9, and that the controller is notched back one notch, to position number 8. Under these conditions, the highest-numbered previously-energized contactor, which is C₁₂, will first become deenergized, and will drop out, closing its negative-circuit off-interlock 35 between the circuits 60 and 72, thereby energizing the operating-coil of the next lower-numbered contactor, which would be C₈, and causing this contactor to close, at which time the four closed contactors would be numbered from C₈ to C₁₁. In like manner, the retrogressive sequence will continue, each time first dropping out the highest-numbered contactor which had been closed, and then, by that closure, drawing in the next lower-numbered contactor; and this retrogressive operation will continue until the

four lowest-numbered contactors C_1 to C_4 are the only ones energized.

This contactor-controlling circuit-arrangement has the serious disadvantage of switch-racing, in the event of a faulty simultaneous electrical energization of a plurality of contactor-controlling coils which ought not to be simultaneously energized, as previously described.

The control-circuits for the operating coils 44 of the twelve relays X_1 to X_{12} are novel, not only in including the rectifiers 47, but also in including the off-interlocks 45 of the first eight relays X_1 to X_8 .

The rectifiers 47, in series with the respective relay-energizing conductors 1 to 12, prevent unwanted and unintended "backstair" circuits, which usually result from some kind of ground or short-circuit on one or more of the wires of the train-line 49, or from a faulty response, or failure to respond, in one of the relays corresponding to X_1 to X_{12} in another cab (not shown). Ordinarily, the relay-energizing wires 1 to 12 are the positive relay-terminals, and the circuit is completed, through other conductors, to the negative relaying terminal (-). Under some faulty operating-conditions, however, one or more of the relay-energizing conductors 1 to 12, or 1' to 12', may become negative, or more negative than another one of these conductors, so that current may flow to one relay-coil through its positive relay-energizing conductor, come back through the negative terminal of another relay-coil, and flow back through the faultily negatively energized relay-energizing conductor, getting back to the negative relay-terminal (-) somewhere out on a faulty train-line conductor. For example, such a fault might be caused by a sticking relay on another cab, or on another motor-driven railway-truck, it being understood that, in multiple-unit operation, the illustrated equipment will be multiplied, with similar equipments located in different cabs or in different trucks, all being connected through the train-line 49. My rectifiers 47 prevent this kind of back-circuits, and thus are needed in order to complete the sequential-interlock relay-protection which is provided by the off-interlocks 45 of my relays, as will now be described.

The negative end of my relay-controlling circuit is novel in including the off-interlocks 45 of the first eight relays X_1 to X_8 . The negative relay-supply terminal (-) is connected to a negative relay-circuit terminal 80, which is extended through the serially connected out-interlocks 45 of the relays X_1 to X_8 , respectively, to successively energize the conductors 81 to 88. The negative terminals of the relay-controlling coils 44 of the first four relays X_1 to X_4 are connected directly to the negative terminal 80; while the negative terminals of the relay-controlling coils of the remaining relays X_5 to X_{12} are connected to the respective conductors 81 to 88. In this way, the negative-circuit off-interlocks 45 of the first eight relays X_1 to X_8 perform, for the relays, the same interlocking functions which are performed, for the contactors, by the positive-circuit (or progressive-sequence) off-interlocks 34 of the first eight contactors C_1 to C_8 , the operation of which has been described.

As a result of the interlocking control-circuits which have been described, both the relays X_1 to X_{12} , and the contactors C_1 to C_{12} will race, if there should be a simultaneous electrical energization which reaches the operating-coils of relays or contactors which ought not to be closed.

simultaneously. It has been pointed out that, in the case of the main-circuit contactors C_1 to C_{12} , the sequential interlocks cannot be omitted under any circumstances, because the contactor-controlling relays and/or their controller-means (including the relay-energizing circuits) are susceptible of faulty relay-operations, including responses and/or non-responses which depart from the desired sequence of operations, as well as including the possibility of simultaneous momentary, or even permanent, responses of a plurality of relays which should not simultaneously respond.

By the simple duplication of the progressive-sequence interlocks 34 which are provided for the contactors; that is, by adding similar interlocks 45 on the relays, I have not stopped switch-racing (by "switch-racing" including relay-racing as well as contactor-racing), but I have established a second racing-contest among the fast-acting relays, with interlocking-means for making sure that the erroneously closing relays, in this race, will promptly be locked out, and re-open again, ultimately leaving only the closing relay or relays which ought to be closed. It insures that the lowest-numbered relays, of the several relays that may be energized simultaneously, always win the "race." And this sorting-out process of the relays, resulting from the racing of the relay-contacts, is so quick that the brief moment during which the erroneously closed relay-contacts 43 are closed, before they are reopened again, will be too quick to cause a response of the corresponding sluggishly moving contactors.

Thus, I have not stopped racing, but I have put the racing among the relays X_1 to X_{12} , where it does no harm, and in this way, I have completely eliminated any racing among the contactors C_1 to C_{12} , where it would do a great deal of harm, as has been above pointed out. And in curing this long-outstanding evil of racing contactors, I have added no apparatus at all (barring the control-circuit backstairs-preventing rectifiers 47), because the relays which were already in use were provided with a number of contacts, enough contacts so that the out-interlocks 45 were readily available at hand, and the introduction of these relay-interlocks 45 into the relay-circuits introduced scarcely no circuit-complexity at all.

While I have described my invention in an extremely simplified form, and in only one illustrative application or form of embodiment, I wish it to be understood that my invention is susceptible of many variations, including the substitution of various equivalents, the omission or addition of various features or parts or additional safeguards, and other changes which will suggest themselves to the skilled workers of the art, as different situations arise. I desire, therefore, that the appended claims shall be accorded the broadest construction consistent with their language.

65 I claim as my invention:

1. Control-equipment characterized by: a plurality of contactors which have to be operated in a predetermined sequence of closings and openings, involving making an operation or operations of each of a plurality of said contactors dependent upon a predetermined previous operation or operations of another contactor or contactors, according to a predetermined law of sequences, each of said contactors having an operating means which includes a contactor-

11

controlling coil which has to be electrically energized in order to cause a contactor-operation in one direction, each of said contactors having a main-circuit contact or contacts which are closed and opened by the operations of that contactor, and each of a plurality of said contactors also having interlocking-means for preventing each of a plurality of said contactors from remaining operated, if a certain other contactor or contactors is operated, in violation of a predetermined prescribed sequence of operations; a plurality of contactor-controlling relays, each of said relays having an operating-means which includes a relay-controlling coil which has to be electrically energized in order to cause a relay-operation in one direction, each of said relays having a contactor-controlling contact or contacts which are closed and opened by the operations of that relay, and each of a plurality of said relays also having interlocking-means for preventing each of a plurality of said relays from remaining operated, if a certain other relay or relays is operated, in violation of a predetermined prescribed sequence of operations; a controller-means for energizing said relay-controlling coils in a predetermined sequence; said relays and/or controller-means being susceptible of faulty relay-operations, including responses and/or non-responses which depart from the desired sequence of operations, and including the possibility of simultaneous momentary initial responses of a plurality of relays which should not simultaneously respond; contactor-energizing circuit-means for putting the energization and deenergization of the contactor-controlling coils under the control of the proper contactor-controlling relay-contacts, said contactor-energizing circuit-means also including interlocking circuit-means for putting the operations of each of a plurality of said contactors under the control of the proper auxiliary contact or contacts of another contactor or contactors in such manner as to maintain said predetermined sequence of contactor-operations so long as the corresponding relays do not have a faulty relay-operation involving the simultaneous initial responses of a plurality of relays which should not simultaneously respond; and relay-interlocking circuit-means for putting the relay-operations under the control of the proper auxiliary contact or contacts of other relays in such manner that, in the event of a simultaneous faulty response of a plurality of relays which should not simultaneously initially respond, the coils of the faultily responding relay or relays will be quickly deenergized by the relay-interlocking circuit-means; the rates of response of said relays being so much faster than the rates of response of said contactors, that said contactors will not be caused to even momentarily respond to the faulty operation of a relay or relays which momentarily respond simultaneously with another relay or relays with which the faultily operating relay or relays should not simultaneously respond, said faultily operating relay or relays immediately returning to their non-operated conditions as a result of the relay-interlocking means.

2. Control-equipment characterized by: a plurality of contactors which have to be operated in a predetermined sequence of closings and openings, involving making an operation or operations of each of a plurality of said contactors dependent upon a predetermined previous operation or operations of another contactor or contactors, according to a predetermined law of sequences, each of said contactors having an operating-means which includes a contactor-controlling coil which has to be electrically energized in order to cause a contactor-operation in one direction, each of said contactors having a main-circuit contact or contacts which are closed and opened by the operations of that contactor, and each of a plurality of said contactors also having an auxiliary control-circuit contact or contacts which are also closed and opened by the operations of that contactor; a plurality of contactor-controlling relays, each of said relays having an operating-means which includes a relay-controlling coil which has to be electrically energized in order to cause a relay-operation in one direction, each of said relays having a contactor-controlling contact or contacts which are closed and opened by the operations of that relay, and each of a plurality of said relays also

12

having an auxiliary control-circuit contact or contacts which are also closed and opened by the operations of that relay; a controller-means for energizing said relay-controlling coils in a predetermined sequence; said relays and/or controller-means being susceptible of faulty relay-operations, including responses and/or non-responses which depart from the desired sequence of operations, and including the possibility of simultaneous momentary initial responses of a plurality of relays which should not simultaneously respond; contactor-energizing circuit-means for putting the energization and deenergization of the contactor-controlling coils under the control of the proper contactor-controlling relay-contacts, said contactor-energizing circuit-means also including interlocking circuit-means for putting the operations of each of a plurality of said contactors under the control of the proper auxiliary contact or contacts of another contactor or contactors in such manner as to maintain said predetermined sequence of contactor-operations so long as the corresponding relays do not have a faulty relay-operation involving the simultaneous initial responses of a plurality of relays which should not simultaneously respond; and relay-interlocking circuit-means for putting the relay-operations under the control of the proper auxiliary contact or contacts of other relays in such manner that, in the event of a simultaneous faulty response of a plurality of relays which should not simultaneously initially respond, the coils of the faultily responding relay or relays will be quickly deenergized by the relay-interlocking circuit-means; the rates of response of said relays being so much faster than the rates of response of said contactors, that said contactors will not be caused to even momentarily respond to the faulty operation of a relay or relays which are quickly deenergized by said relay-interlocking circuit-means.

3. Control-equipment characterized by: a plurality of contactors which have to be operated in a predetermined sequence of closings and openings, involving making an operation or operations of each of a plurality of said contactors dependent upon a predetermined previous operation or operations of another contactor or contactors, according to a predetermined law of sequences, each of said contactors having an operating-means which includes a contactor-controlling coil which has to be electrically energized in order to cause a contactor-operation in one direction, each of said contactors having a main-circuit contact or contacts which are closed and opened by the operations of that contactor, and each of a plurality of said contactors also having interlocking-means for preventing each of a plurality of said contactors from remaining operated, if a certain other contactor or contactors is operated, in violation of a predetermined prescribed sequence of operations; a plurality of contactor-controlling relays, each of said relays having an operating-means which includes a relay-controlling coil which has to be electrically energized in order to cause a relay-operation in one direction, each of said relays having a contactor-controlling contact or contacts which are closed and opened by the operations of that relay, and a plurality of said relays having relay-interlocking means for providing for a predetermined sequence of relay-operations; a controller-means for energizing said relay-controlling coils in a predetermined se-

13

quence, said controller-means being subject to short-circuit conditions which tend to simultaneously energize a plurality of relays which should not simultaneously respond; and contactor-energizing circuit-means for putting the energization and deenergization of the contactor-controlling coils under the control of the proper contactor-controlling relay-contacts; the rates of response of said relays being considerably faster than the rates of response of said contactors.

4. Control-equipment characterized by: a plurality of contactors which have to be operated in a predetermined sequence of closings and openings, involving making an operation or operations of each of a plurality of said contactors dependent upon a predetermined previous operation or operations of another contactor or contactors, according to a predetermined law of sequences, each of said contactors having an operating-means which includes a contactor-controlling coil which has to be electrically energized in order to cause the contactor to respond by moving from its non-responsive condition to its responsive condition, each of said contactors having a main-circuit make-contact or contacts which are closed by the response of that contactor, and each of a plurality of said contactors also having an auxiliary control-circuit back-contact or contacts which are opened by a response of that contactor; a plurality of contactor-controlling relays, each of said relays having an operating-means which includes a relay-controlling coil which has to be electrically energized in order to cause the relay to respond by moving from its non-responsive condition to its responsive condition, each of said relays having a contactor-controlling make-contact or contacts which are closed by the response of that relay, each of a plurality of said relays also having an auxiliary control-circuit back-contact or contacts which are opened by a response of that relay, and the several relay-controlling coils having coil-leads which are subject to short-circuit conditions wherein supposedly insulated leads are faultily connected together; contactor-energizing circuit-means for energizing the respective contactor-controlling coils, the energizing-circuit of each of said contactor-controlling coils serially including a contactor-controlling make-contact or contacts of a relay or relays, and the energizing-circuit of each of a plurality of said contactor-controlling coils serially including also a control-circuit back-contact or contacts of another contactor or contactors in accordance with a predetermined law of contactor-sequences; controller-means having a plurality of contact-members; relay-energizing circuit-means for energizing the respective leads of the relay-controlling coils, the energizing-circuit for each relay serially including a contact-member of said controller-means, the energizing-circuit for each of a plurality of said relays serially including also a control-circuit back-contact or contacts of another relay

14

or relays in accordance with a predetermined law of relay-sequences; the rates of responses of said relays being considerably faster than the rates of response of said contactors.

5. The invention as defined in claim 4, characterized by the relay-energizing circuit-means including a source of direct-current energy for energizing the relay-controlling coils, in combination with a unidirectionally conducting rectifying-means in series circuit relation to each of a plurality of said relay-controlling coils.

6. The invention as defined in claim 4, characterized by said controller-means being subject to faulty operating-conditions wherein supposedly separately controlled contact-members are erroneously simultaneously closed.

7. The invention as defined in claim 6, characterized by the relay-energizing circuit-means including a source of direct-current energy for energizing the relay-controlling coils, in combination with a unidirectionally conducting rectifying-means in series circuit relation to each relay-controlling coil.

8. Control-equipment for causing a group of electrically controlled main-circuit contact-making devices to operate sequentially, according to a predetermined sequence, comprising the combination, with said main-circuit contact-making devices, of a group of electrically controlled auxiliary-circuit contact-making devices for electrically controlling said main-circuit contact-making devices, at least some of the contact-making devices of each group having interlock-providing auxiliary contacts, and interlocking circuits for each group, using the interlocks of that group in such fashion as to maintain a desired predetermined sequence if the initially operable main-circuit or auxiliary-circuit contact-making device is properly selected, as the case may be, but causing a race between the contact-making devices of that group, in the event of the simultaneous initial energization of devices which ought not operate simultaneously, in that group; the auxiliary-circuit contact-making devices being so much faster than the main-circuit contact-making devices that, in the event of a race of the auxiliary-circuit contact-making devices, the race will be over, and the erroneously responding auxiliary-circuit contact-making devices will have been restored, by their interlocks, to a non-responsive condition, before the undesired main-circuit contact-making devices will have received a response-producing amount of energization.
